United States Patent Office

Des. 207,422

Patented Apr. 11, 1967

207,422

WEATHER INSTRUMENT

Ellsworth R. Danz, La Salle, and David W. Miley and
Ralph H. Preiser, Peru, Ill., assignors to General Time
Corporation, Stamford, Conn., a corporation of Dela-
ware

Filed June 27, 1966, Ser. No. 2,818

Term of patent 14 years

(Cl. D52—7)

FIG.1

FIG.2

FIG.3

FIG. 5

FIG. 4

FIG. 1 is a perspective view of a weather instrument showing our new design as viewed from the front left thereof;

FIG. 2 is a top plan view of said instrument;

FIG. 3 is a front elevational view thereof;

FIG. 4 is a rear elevational view thereof;

FIG. 5 is a left side elevational view of said instrument, the right side being substantially a mirror image thereof.

We claim:

The ornamental design for a weather instrument, substantially as shown and described.
